HARP CONSTRUCTION FOR SUPPORTING
ELECTRIC LAMP SHADES

Carl Bramming, Anderson, Ind., assignor to Aladdin Industries, Incorporated, Chicago, Ill., a corporation of Illinois

Application September 9, 1947, Serial No. 773,059

9 Claims. (Cl. 240—148)

1

The invention comprises a harp construction for supporting shades of electric lamps, which includes a tubular base around and spaced from a vertically disposed lamp socket and secured to the pedestal or other support for said socket, and a harp bracket supported by said base and extending upwardly therefrom in the form of a loop around the lamp bulb supported by the socket, said bracket having at its top or mid-portion a fixture for supporting a shade around said bracket and said bulb. The present invention is directed to the manner of supporting the harp bracket from the harp base and to the construction of these parts by which the advantages of the invention are secured, which advantages are first, imparting positive support to the harp bracket, second, facilitating quick and easy assembling of said parts, and third, producing said parts by simple and inexpensive tool operations to the end that the cost of making the harp construction may be reduced to a minimum.

It is the object of the invention to accomplish the results described, by making the harp bracket of a bent rod of resilient metal having outwardly extending lower ends engaging and fitting correspondingly disposed apertures through the side wall of the tubular base of the construction, and holding said ends in said apertures to prevent movement of said ends axially of said tubular base, by positive and outwardly directed thrusts of the lower end portions of said bracket against the side wall of said base which surrounds said end portions with a substantial clearance space between it and the lamp socket also surrounded by said side wall; it is a further object of the invention to restrain said bracket against turning movement on its outwardly extending lower ends relatively to said tubular base, by providing said bracket above said lower ends with outwardly extending humps projecting through corresponding slots through the side wall of said tubular base, so that the substantial outward and opposite thrusts on the lower end portions of the bracket against the side wall of the base of the harp, securely hold the lower ends of the bracket in the base apertures and at the same time hold the bracket humps in the base slots, thereby preventing movement of the bracket in any direction relatively to the base, unless the lower portions of the bracket are forcibly pressed together to disengage the bracket ends and humps from the base apertures and slots, which may be done at any time if it is desired to disassemble the harp structure.

The above and other objects of the invention 55

will be better understood by reference to the accompanying drawings illustrating a preferred embodiment thereof, in which:

Fig. 1 shows the harp construction in place on an electric lamp, the harp bracket and lamp socket and bulb being shown in front elevation and the harp base and upper portion of the lamp pedestal or support being shown in central, vertical, sectional view taken along the line 1—1 in

Fig. 2, and detail view of the harp bracket.

Fig. 2 shows the harp and lamp structure, including the upper portion of the lamp support, in side elevation. Similar numerals are used throughout the several views.

As shown in the drawings, a socket 1 for the lamp is shown as supported with its axis in vertical position, by an arm 2 extending from an internally threaded sleeve 3, holding a threaded mounting collar 4 tightly against the bottom, horizontal wall of the harp base 5. The collar 4 is screwed on to the upper end of the pedestal 6 of the lamp, illustrating any desired support therefor, and a vertically disposed lamp bulb 7 is shown in the socket 1. The socket 1 is shown as provided with electric conductors 8 and a connecting plug 9, said socket being also preferably provided with a switching mechanism 10 to control current flow to the bulb 7.

All of the parts so far described, excepting the harp base 5, are of known construction and do not per se constitute in the form shown, an essential part of the present invention, being shown merely to illustrate the purpose of the invention and its contemplated relation to known lamp structures.

The harp base 5 is preferably of formed sheet metal, and includes a horizontal bottom wall 11 supported as described, or in an equivalent manner by the lamp structure, to impart stable support to the harp structure. From the outer edge of the wall 11, the base 5 continues upwardly in the form of an integral and tubular side wall 12 which is preferably cylindrical, surrounding and substantially spaced from the socket 1, and provided in its lower portion with opposite apertures 13, receiving and closely fitting the lower horizontal ends 14 integral with and extending outwardly from the lower portions of the harp bracket 15.

The bracket 15 preferably comprises a rod of resilient metal bent to the form described and so formed that in use its lower portions are in the space between the wall 12 and the socket 1, with the upper part of the bracket sufficiently compressed to exert substantial out-

ward thrusts by its lower portions against the wall 12 to securely hold the bracket ends 14, in the apertures 13, against accidental removal therefrom.

Above the ends 14, the bracket 15 is provided with integral humps 16, extending outwardly through vertical slots 17, therefor in the wall 12, which slots closely fit said humps laterally of said slots. Above the slots 17, the wall 12 is preferably provided at its upper open end, with a rolled bead 18 stiffening the upper end of said wall and providing a finish for the upper end of the base 5.

Above the harp base 5, the bracket 15 extends upwardly and around the bulb 1 with the general form of said bulb and spaced sufficiently therefrom to permit the ready insertion of the bulb into and the removal of the same from the socket 1. At its upper mid-portion the bracket 15 carries a shade supporting fixture 19 which may have any known form and which preferably frictionally engages the bracket 15 so that said fixture and the shade supported by it around said bracket and around the bulb 1, may be adjusted or tilted angularly as desired relatively to the bracket and bulb.

The spacing of the wall 12 from the socket 1 is sufficient to readily permit the insertion and removal as desired, of the ends 14, and humps 16, in assembling and disassembling the bracket 15 and base of the harp.

In the unstressed condition of the bracket 15 removed from the base 5, the lower portions of said bracket are spaced from each other a much greater distance than would permit the insertion of said lower portions into the open upper end of the tubular wall 12; to effect said insertion in assembling the parts, said lower end portions are forcibly pressed toward each other until the ends 14, and humps 16, will enter the tubular wall 12, thereby developing in the bracket 15 substantial internal stresses tending to separate its lower portions; when said ends and said humps are moved into alignment with the apertures 13 and slots 17, said internal stresses forcibly separate the lower portions of the bracket, but only for the small distance required to move the ends 14 into the apertures 13 and the humps 16 into the slots 17, thereby but slightly decreasing said internal stresses and leaving the major portion thereof operative to forcibly hold said parts in their assembled relation, thereby giving the bracket 15 substantial and stable support. The material or diameter of rod, or both, of which the bracket 15 is made, are selected to facilitate the development of the internal stresses referred to; in that connection, the selection of a rod diameter that is substantial, has the further advantage of providing without the use of any additional part or parts, a surface of substantial area of frictional engagement between the bracket 15 and the shade fixture 19, insuring the holding of the shade in any adjusted or tilted position on the bracket.

It will be noted that only the simplest of mechanical operations are required in making the base 5 and the bracket 15 of the harp structure. In making the base, after it is formed with its integral side and bottom walls, the only further necessary operations are perforating operations to make the apertures 13 and slots 17, the bead 18 being optional depending on the thickness of metal of the wall 12; it may be noted that it is not necessary for the ends of the humps 16 to exert outward thrusts on the wall 12, since the

only necessary action of the humps 16 is to closely fit the slots 17 laterally of said slots to prevent turning of the bracket 15 on its lower ends relatively to the base 5, in which case said outward thrusts are exerted entirely by the lower ends of the bracket 15 near the bottom wall 11, thus facilitating making the base 5 of relatively thin metal without danger of its deformation due to said outward thrusts. In making the bracket 15, where the same is made of a round metal rod which is preferable, only simple wire or rod-bending or forming operations are required. Thus the harp structure described is not only effective in accomplishing its intended purposes, but it is also inexpensive to manufacture.

While I have shown my invention in the particular embodiment described, I do not limit myself thereto as I may employ equivalents thereof without departing from the scope of the appended claims.

I claim:

1. In a harp construction for supporting shades of electric lamps, the combination of a lamp bulb socket, a support rigidly secured to said socket, a tubular harp base rigidly secured to said support and having a side wall around and substantially spaced from said socket, and a harp bracket having its lower end portions within said side wall and extending above said side wall in an integral loop around and to clear the lamp bulb used in said socket, each of said lower end portions having a pair of spaced and outwardly extending projections, and said side wall having a pair of perforations for receiving said pair of projections from each of said harp end portions, one of said perforations of each pair closely fitting one projection of a corresponding pair laterally and axially of said harp base and the other of said pair of perforations closely fitting laterally the other of said corresponding pair of projections, said bracket being resilient and having internal stresses tending to move its said lower portions away from each other and positively and forcibly holding said projections in said perforations, thereby restraining said harp bracket against movement relatively to said harp base and providing rigid support for said bracket in said base.

2. In a harp construction for supporting shades of electric lamps, the combination of a lamp bulb socket, a support rigidly secured to said socket, a tubular harp base rigidly secured to said support and having a side wall around and substantially spaced from said socket, and a harp bracket having its lower end portions within said side wall and extending above said side wall in an integral loop around and to clear the lamp bulb used in said socket, each of said lower end portions having a pair of spaced and outwardly extending projections, and said side wall having a pair of perforations for receiving said pair of projections from each of said harp end portions, one of said perforations of each pair closely fitting one projection of a corresponding pair laterally and axially of said harp base and the other of said pair of perforations closely fitting laterally the other of said corresponding pair of projections, said bracket being resilient and having internal stresses tending to move its said lower portions away from each other and positively and forcibly holding said projections in said perforations, thereby restraining said harp bracket against movement relatively to said harp base and providing rigid support for said bracket in said base, one of said projections

from each of said end portions being cylindrical and the other of said projections from each of said end portions being a hump formed from the corresponding end portion.

3. In a harp construction for supporting shades of electric lamps, the combination of a lamp bulb socket, a support rigidly secured to said socket, a tubular harp base rigidly secured to said support and having a side wall around and substantially spaced from said socket, and a harp bracket having its lower end portions within said side wall and extending above said side wall in an integral loop around and to clear the lamp bulb used in said socket, each of said lower end portions having a pair of spaced and outwardly extending projections, and said side wall having a pair of perforations for receiving said pair of projections from each of said harp end portions, one of said perforations of each pair closely fitting one projection of a corresponding pair laterally and axially of said harp base and the other of said pair of perforations closely fitting laterally the other of said corresponding pair of projections, said bracket being resilient and having internal stresses tending to move its said lower portions away from each other and positively and forcibly holding said projections in said perforations, thereby restraining said harp bracket against movement relatively to said harp base and providing rigid support for said bracket in said base, the spacing of said side wall from said socket affording a clearance space for said projections for assembling and disassembling purposes.

4. In a harp construction for supporting shades of electric lamps, the combination of a lamp bulb socket, a support rigidly secured to said socket, a tubular harp base rigidly secured to said support and having a side wall around and substantially spaced from said socket, and a harp bracket having its lower end portions within said side wall and extending above said side wall in an integral loop around and to clear the lamp bulb used in said socket, each of said lower end portions having a pair of spaced and outwardly extending projections, and said side wall having a pair of perforations for receiving said pair of projections from each of said harp end portions, one of said perforations of each pair closely fitting one projection of a corresponding pair laterally and axially of said harp base and the other of said pair of perforations closely fitting laterally the other of said corresponding pair of projections, said bracket being resilient and having internal stresses tending to move its said lower portions away from each other and positively and forcibly holding said projections in said perforations, thereby restraining said harp bracket against movement relatively to said harp base and providing rigid support for said bracket in said base, one of said projections from each of said end portions being cylindrical and the other of said projections from each of said end portions being a hump formed from the corresponding end portion, the spacing of said side wall from said socket affording a clearance space for said projections for assembling and disassembling purposes.

5. A harp fixture for supporting lamp shades comprising a tubular harp base adapted for rigid support from a lamp pedestal and extending at a distance around the socket of the lamp, and a harp bracket of resilient metal rod including an upwardly extending loop portion and integral lower end portions inside of said harp base, each

of said lower end portions having a pair of spaced and outwardly extending projections, the side wall of said harp base being provided with a pair of perforations for receiving said pair of projections from each of said harp end portions, one of said perforations of each pair closely fitting one projection of a corresponding pair laterally and axially of said harp base and the other of said pair of perforations closely fitting laterally the other of said corresponding pair of projections, and said bracket having internal stresses positively pressing said lower end portions outwardly against said side wall and said projections into said perforations, thereby providing rigid support for said bracket in said base.

6. A harp fixture for supporting lamp shades comprising a tubular harp base adapted for rigid support from a lamp pedestal and extending at a distance around the socket of the lamp, and a harp bracket of resilient metal rod including an upwardly extending loop portion and integral lower end portions inside of said harp base, each of said lower end portions having a pair of spaced and outwardly extending projections, the side wall of said harp base being provided with a pair of perforations for receiving said pair of projections from each of said harp end portions, one of said perforations of each pair closely fitting one projection of a corresponding pair laterally and axially of said harp base and the other of said pair of perforations closely fitting laterally the other of said corresponding pair of projections, and said bracket having internal stresses positively pressing said lower end portions outwardly against said side wall and said projections into said perforations, thereby providing rigid support for said bracket in said base, one of said projections from each of said end portions being cylindrical and the other of said projections from each of said end portions being a hump formed from the corresponding end portion.

7. A harp fixture for supporting lamp shades comprising a tubular harp base adapted for rigid support from a lamp pedestal and extending at a distance around the socket of the lamp, and a harp bracket of resilient metal rod including an upwardly extending loop portion and integral lower end portions inside of said harp base, each of said lower end portions having a pair of spaced and outwardly extending projections, the side wall of said harp base being provided with a pair of perforations for receiving said pair of projections from each of said harp end portions, one of said perforations of each pair closely fitting one projection of a corresponding pair laterally and axially of said harp base and the other of said pair of perforations closely fitting laterally the other of said corresponding pair of projections, and said bracket having internal stresses positively pressing said lower end portions outwardly against said side wall and said projections into said perforations, thereby providing rigid support for said bracket in said base, the spacing of said side wall from said socket affording a clearance space for said projections for assembling and disassembling purposes.

8. A harp fixture for supporting lamp shades comprising a tubular harp base adapted for rigid support from a lamp pedestal and extending at a distance around the socket of the lamp, and a harp bracket of resilient metal rod including an upwardly extending loop portion and integral lower end portions inside of said harp base, each of said lower end portions having a pair of spaced and outwardly extending projections, the side

wall of said harp base being provided with a pair of perforations for receiving said pair of projections from each of said harp end portions, one of said perforations of each pair closely fitting one projection of a corresponding pair laterally and axially of said harp base and the other of said pair of perforations closely fitting laterally the other of said corresponding pair of projections, and said bracket having internal stresses positively pressing said lower end portions outwardly against said side wall and said projections into said perforations, thereby providing rigid support for said bracket in said base, one of said projections from each of said end portions being cylindrical and the other of said projections from each of said end portions being a hump formed from the corresponding end portion, the spacing of said side wall from said socket affording a clearance space for said projections for assembling and disassembling purposes.

9. Means for supporting a lamp shade upon a lamp pedestal, comprising, in combination, a tubular harp base extending circumferentially of the socket of the lamp, means for supporting said base above said pedestal, and a harp bracket of resilient metal rod having an upwardly extending loop portion and lower end portions extending into said base, each of said end portions having a

pair of spaced and outwardly extending projections, the side wall of said harp base being provided with a pair of perforations for receiving said pair of projections from each of said harp end portions, one of said perforations of each pair closely fitting one projection of a corresponding pair laterally and axially of said harp base and the other of said pair of perforations closely fitting laterally the other of said corresponding pair of projections, and said bracket having internal stresses positively pressing said lower end portions outwardly against said side wall and said projections into said perforations.
